UNITED STATES PATENT OFFICE

CLAUDIUS GIVAUDAN, OF LYON, FRANCE

APPARATUS FOR USE IN HAND PRINTING ON FABRIC OR PAPER

Application filed August 21, 1928, Serial No. 301,031, and in France August 22, 1927.

The present invention relates to apparatus for use in hand-printing on fabric or paper.

It is known that the printing of fabric or paper by hand is done by means of plates bearing the appropriate engravings, which are applied by hand to the fabric or paper previously stretched on a table of suitable dimensions. A plate is required for each colour of the design to be applied, and the plates, in order to be easily handled, must be of relatively small dimensions. The printing of a piece of fabric, or of a roll of paper, therefore necessitates a large number of applications of the plate. In order that the colours may be correctly disposed in relation to each other, and that the pattern of a given coloured plate may be correctly aligned with the patterns of the adjacent plates of the same colour, the operator must mark exactly the position of the plate which he has in his hand, before applying it to the fabric or paper, which is an extremely delicate operation, requiring great skill and much time.

Printing machines obviously dispose of this inconvenience, but they are economical only for prints effected on large surfaces of fabric or paper. Where designs are to be printed only on a small number of pieces of fabric, hand labour is preferable.

The present invention completely disposes of the difficulty of adjusting the positions of the plates to obtain correct register of superposed designs and proper alignment of adjacent sections of the design. According to the invention a carriage, carrying the plates and movable longitudinally of the table on which rests the fabric or paper to be printed on, is adapted to engage adjustable stops which arrest the carriage in successive positions corresponding to each transverse row of sections of which the design is made up.

Means are also provided on the carriage for positioning the plates transversely of the fabric or paper, for printing the transverse rows of sections of the design.

On the annexed drawings:

Fig. 1 is a partial plan view of the apparatus.

Fig. 2 is an end view of the same.

Fig. 3 is an enlarged plan view of a transverse carriage.

Fig. 4 is a section of the same on line IV—IV (Fig. 3).

Fig. 5 is a section of the same on line V—V (Fig. 3).

Fig. 6 is an enlarged side view of the carriage stops with their adjustable gauge.

Fig. 7 is a side view of the carriage-locking device.

Fig. 8 is a plan view of the same, with parts in section.

Fig. 9 is a section on line IX—IX (Fig. 7).

Fig. 10 is a section on line X—X (Fig. 7).

Fig. 11 is a bottom plan view of a printing plate.

Fig. 12 is a perspective view of the same.

Fig. 13 is a plan view of a stencil frame and related parts.

Fig. 14 is a partial section on line XVI—XVI (Fig. 13).

Fig. 15 is a partial section on line XVII—XVII (Fig. 14).

The table 1 (Figs. 1 and 2) is one commonly used for hand printing, the fabric to be printed being fixed thereon—by gluing or otherwise.

Each longitudinal side of the table is provided with a rail 2 or 3 which support a carriage comprising a frame 4 and axles 5 carrying wheels 6 and 7. Wheels 6 are cut with V-shaped grooves in order to guide the carriage and wheels 7 are used only as support wheels resting on rail 3.

The carriage is provided with two transverse beams 8 (Figs. 1, 3 and 4) each having an axial inverted T-shaped groove 9; these beams form slides for a number of small transverse carriages 10 (Fig. 1).

Each transverse carriage (Figs. 3, 4 and 5) comprises a fixed member 11 which is locked in position by a bolt 12 and a nut 13. A double-pitch screw 14 connects member 11 with a sliding plate 15 which supports a second sliding plate 16. Two bolts 17 pass through holes provided in plate 15 and through elongated apertures 18 provided in plate 16. These bolts form guides for plates 15 and 16, plate 15 sliding transversely and plate 16 longitudinally, with respect 100

to the table 1. Bolts 17 are provided with springs 20 and collars 21, in such a way that, by tightening the nuts 22, plates 15 and 16 may be locked on beam 8, and that, when nuts 22 are loosened, springs 20 act as brakes to maintain the plates pressed onto the beam, in order to make the adjustment easier.

A double-pitch screw 23 connects plates 15 and 16 together.

10 Beams 8 are adjustable on the frame 4 in order that their distance may be varied at will.

15 The plate 16 carries, by means of stays 24, a smaller plate 25 provided with a vertical pin 26 adapted to receive the lug 27 of a printing plate 28. As shown, Figs. 4 and 5, small spring-acted pistons 29 are arranged to maintain the printing plate 28 out of contact with the fabric to be printed. In the 20 drawings, the springs are represented at 30; but any form of spring-acted member could be employed. These members can also be fixed to the printing plate so as to act on plate 25.

25 Each printing plate 28 (Figs. 11 and 12) is of the kind commonly used in hand-printing and is inked in a manner well known in the hand-printing art, but it is provided with two side lugs 27 and 31. Lug 27 has a hole 32 adapted to cooperate with a pin such as 26; lug 31 has an elongated opening 33 also adapted for cooperation with a pin 26, but with a liberal play along the axis of the plate.

30 35 When all necessary adjustments have been made, a printing plate such as 28 is placed between two opposite transverse carriages 10, as shown in Fig. 1. The pins 26 pass through hole 32 and opening 33, the axial play of the latter avoiding any accidental jamming. The printing plate being supported by pistons 29, does not contact with the fabric. By giving a strong vertical blow on the printing plate it depresses the pistons 29 and contacts with the fabric, a good and well-adjusted print being obtained.

40 The longitudinal position of the principal carriage is insured by means of stops arranged on the side of rail 2 (Figs. 2, 6 and 7). 45 These stops are in the form of plates 34 having a central notch 35 and two inclined upper edges 36, and are fixed by means of bolts 37, to a beam 38 provided with an axial T-shaped groove 39, this beam 38 being fixed on the 50 side of rail 2.

55 60 The frame 4 of the principal carriage is provided with a vertically movable key 40, loaded by a spring 41 (Figs. 7, 8 and 9) and adapted to cooperate with the notches 35. 65 When the carriage is moved, the key 40 is raised by one of edges 36 and is pushed by spring 41 into a notch 35. The carriage is then locked in position. By raising key 40 (by means of a knob 42), the carriage is freed 70 and may be moved to another position.

Some fabrics are very easily and unequally affected by moisture and it happens that the central portions of a piece of fabric stretched on a printing table are displaced by several centimeters during an operation.

70 In order to correct these displacements without re-adjusting the stops 34, the key 40 is not fixed to the frame 4, but to a carriage 43 which is slideable on frame 4. This carriage is U-shaped and is closed by a back plate 44. 75 Elongated openings (not shown) are of course provided for key 40 in the frame 4. Carriage 43 is controlled by a double-pitch screw 45, screwed in a nut 46 fixed to plate 44 and in a nut 47 fixed to frame 4. The head 80 of screw 45 is provided with graduations cooperating with a pointer 49 fixed to frame 4, as it is well-known in micrometric devices.

The adjustment of the transverse carriages 10 is easily obtained by means of a sheet of 85 transparent material, for example celluloid on which the pattern and its axes are reproduced. The pattern and its axes are also reproduced on a sheet of paper which is fixed on table 1 and which is wide enough to cover 90 the width of the fabric to be printed and at least twice as long as the useful length of a printing plate. The sheet of transparent material is fixed onto a printing plate and the plate is placed in position on the machine, the 95 carriages 10 being adjusted until the axes drawn on the sheet of celluloid exactly cover the axes drawn on the sheet of paper. All the carriages 10 may thus be correctly adjusted.

100 The last adjustment to be made is that of stops 34. It may easily be performed with the same sheet of celluloid fixed on a printing plate. The principal carriage is moved until the transverse axis of the celluloid exactly 105 covers another transverse axis of the sheet of paper. The corresponding stop 34 is thus adjusted. The adjustment of the other ones is done by means of a gauge comprising a threaded rod 58 (Fig. 6) and two disks 59 adjustable on it by means of nuts 60. This 110 gauge is adjusted in such a way that disks 59 simultaneously engage the notches 35 of the two first stops 34. It will be readily understood that such a gauge permits the adjustment of the third stop from the second one, of the fourth stop from the third one, etc. . . .

115 Of course, the printing plate employed for the adjustment may be a special plate having the same dimensions as the printing plates to be used, but not engraved.

120 The machine, thus adjusted, permits an unskilled worker to perform any printing work with any number of dyes.

125 The machine may also be used for printing by means of stencils (Figs. 13, 14 and 15).

The stencil 61 is fixed to a frame 62 as usual. This frame is provided with four lugs 63 forming its corners and with a fifth one 64 on one of its edges. It is placed between beams 130

8 on the principal carriage of the machine and three transverse carriages 10 are used for its adjustment, two of which cooperate with two lugs 63 and the third one with lug 64. As in the case of printing plates, one lug is provided with a hole corresponding with the pins of the transverse carriages, the two other lugs having elongated apertures.

Since the raising up of the stencil frame is a delicate operation, the carriage is provided with means for automatically insuring it. These means comprise two rotatable shafts 65 each provided with two pulleys 66. Strings 67 (Fig. 14) are fixed to lugs 63 and to pulleys 66. Each shaft 65 is provided with a square 68 (Fig. 15) on which acts a finger 69 pressed by a spring 70. Knobs 71 permit an easy hand-control of the shafts.

When strings 67 are adjusted, by turning shafts 65 for a quarter or half a turn, frame 62 may be raised to the desired height.

The adjustment of strings 67 is insured by loosening pulleys 66 on shafts 65 and locking them again at the desired position. This is done by means of split collars 72 which are integral with pulleys 66.

Fig. 14 shows the usual dye scraper 73.

The pins employed on carriages 10 are preferably higher than those used for printing plates. Fig. 4 shows in dash-and-dot lines such a pin 26', which permits the stencil frame to be positively raised without its lugs being disengaged from the pins.

Strings 67 are preferably attached to lugs 63 by means of hooks or the like to permit the stencil frame to be easily removed when necessary.

Of course, four carriages 10 could equally well be used, each one cooperating with a lug 63.

I claim:

1. An apparatus for use in printing on fabrics and the like by means of hand-operated devices such as printing plates or stencils, comprising a table on which the fabric or the like to be printed is stretched; a carriage movable longitudinally of said table, said carriage being provided with means whereby the hand-operated printing devices may be correctly adjusted in a transverse direction over said table; and a plurality of adjustable means for locking said carriage in a number of different positions, whereby said hand-operated printing devices may be correctly adjusted in longitudinal direction.

2. An apparatus for use in printing on fabrics and the like by means of hand-operated devices such as printing plates or stencils, comprising a table on which the fabric or the like to be printed is stretched; a carriage movable longitudinally of said table, said carriage being provided with means whereby the hand-operated printing devices may be correctly adjusted in a transverse direction over said table; locking means adjustable along

said table; means supported by said carriage and adapted to cooperate with said locking means; and means whereby said carriage-supported means may be adjusted with respect to said carriage.

3. An apparatus for use in printing on fabrics and the like by means of hand-operated devices such as printing plates or stencils, comprising a table on which the fabric or the like to be printed is stretched; rails fixed on each side of said table longitudinally of the same; a carriage movable on said rails; means supported by said carriage whereby the hand-operated printing devices may be correctly adjusted in a transverse direction over said table; locking means adjustable along one side of said table; means supported by said carriage and adapted to cooperate with said locking means; and means whereby said second-mentioned carriage-supported means may be adjusted with respect to said carriage.

4. An apparatus for use in printing on fabrics and the like by means of hand-operated devices such as printing plates or stencils, comprising a table on which the fabric or the like to be printed is stretched; rails fixed on each side of said table longitudinally of the same; a carriage movable on said rails; means supported by said carriage whereby the hand-operated printing devices may be correctly adjusted in a transverse direction over said table; a plurality of stops adjustable along one side of said table, each comprising a central notch; a movable key supported by said carriage and adapted to cooperate with the notches of said stops for locking said carriage; hand-operated means whereby said movable key may be disengaged from said notches; and means whereby said movable key may be adjusted in a longitudinal direction with respect to said carriage.

5. An apparatus for use in printing on fabrics and the like by means of hand-operated devices such as printing plates or stencils, comprising a table on which the fabric or the like to be printed is stretched; rails fixed on each side of said table longitudinally of the same; a carriage movable on said rails; means supported by said carriage whereby the hand-operated printing devices may be correctly adjusted in a transverse direction over said table; a plurality of stops adjustable along one side of said table, each comprising a central notch; an auxiliary carriage longitudinally slidable over said first-mentioned carriage; means whereby said auxiliary carriage may be adjusted in position on said first-mentioned carriage; a movable key supported by said auxiliary carriage and adapted to cooperate with the notches of said stops for locking said carriage; and hand-operated means whereby said movable key may be disengaged from said notches.

6. An apparatus for use in printing on

fabrics and the like by means of hand-operated devices such as printing plates or stencils, comprising a table on which the fabric or the like to be printed is stretched; a carriage movable longitudinally of said table; a plurality of adjustable means supported by said table and adapted to lock said carriage in a number of different positions; two sets of transversely adjustable carriages supported by said first mentioned carriage over said table; and means supported by said transversely adjustable carriages whereby a hand-operated printing device may be adjusted in a transverse position with respect to said table by means of at least one carriage of each one of said sets.

7. An apparatus for use in printing on fabrics and the like by means of hand-operated devices such as printing plates or stencils, comprising a table on which the fabric or the like to be printed is stretched; a carriage movable longitudinally of said table; a plurality of adjustable means supported by said table and adapted to lock said carriage in a number of different positions; two sets of carriages transversely adjustable on said first-mentioned carriage and supported by the same over said table; and means transversely and longitudinally adjustable on said second-mentioned carriages whereby a hand-operated printing device may be adjusted in a transverse position with respect to said table, by means of at least one carriage of each one of said sets.

8. An apparatus for use in printing on fabrics and the like by means of hand-operated devices such as printing plates or stencils, comprising a table on which the fabric or the like to be printed is stretched; a carriage movable longitudinally of said table; a plurality of adjustable means supported by said table and adapted to lock said carriage in a number of different positions; and two sets of transversely adjustable carriages supported by said first-mentioned carriage over said table, each one comprising a block transversely adjustable on said first-mentioned carriage, a first plate transversely slidable on said first-mentioned carriage, a second plate longitudinally slidable on said first plate, and a second double-pitch screw adapted to control the longitudinal position of said second plate with respect to said first plate, and means supported by said second plate whereby a hand-operated printing device may be adjusted by means of at least one carriage of each one of said sets.

9. An apparatus for use in printing on fabrics and the like by means of hand-operated devices such as printing plates or stencils, comprising a table on which the fabric or the like to be printed is stretched; a carriage movable longitudinally of said table; a

plurality of adjustable means supported by said table and adapted to lock said carriage in a number of different positions; two sets of carriages transversely adjustable on said first-mentioned carriage and supported by the same over said table; pins on said second-mentioned carriages; and perforated lugs provided on said hand-operated devices, said perforated lugs being adapted to cooperate with said pins, whereby a hand-operated printing device may be adjusted in a transverse position with respect to said table by means of at least one carriage of each one of said sets.

10. An apparatus for use in printing on fabrics or the like by means of hand-operated devices such as printing plates or stencils, comprising a table on which the fabric or the like to be printed is stretched; a carriage movable longitudinally of said table; a plurality of adjustable means supported by said table and adapted to lock said carriage in a number of different positions; means supported by said carriage whereby the hand-operated printing devices may be correctly adjusted in a transverse position over said table; and hand-operated means for raising said hand-operated printing devices to a desired height above said table.

11. An apparatus for use in printing on fabrics and the like by means of hand-operated devices such as printing plates or stencils, comprising a table on which the fabric or the like to be printed is stretched; a carriage movable longitudinally of said table, a plurality of adjustable means supported by said table and adapted to lock said carriage in a number of different positions; means supported by said carriage whereby the hand-operated printing devices may be correctly adjusted in a transverse position over said table; rotatable shafts supported by said carriage; pulleys keyed on said shafts; strings fixed by one end to the hand-operated printing devices and by the other end to said pulleys; and means for rotating said shafts by hand to raise said hand-operated printing devices.

12. An apparatus for use in printing on fabrics and the like by means of hand-operated devices such as printing plates or stencils, comprising a table on which the fabric or the like to be printed is stretched; a carriage movable longitudinally of said table; a plurality of adjustable means supported by said table and adapted to lock said carriage in a number of different positions; means supported by said carriage whereby the hand-operated printing devices may be correctly adjusted in a transverse direction over said table; and spring means adapted to maintain said hand-operated printing devices out of contact with the surface to be printed until they are pressed by hand against said surface.

13. In apparatus as claimed in claim 3, a wheeled carriage comprising guiding and supporting wheels rolling on one carriage-supporting rail and supporting wheels rolling on the other one.
14. In apparatus as claimed in claim 4, a gauge for permitting the adjustment of the carriage-locking stops, said gauge comprising a threaded rod; two disks thereon, said disks being intended to cooperate with the notches of two successive stops; and nuts for locking said disks in position on said rod when required.
15. In apparatus as claimed in claim 7, a carriage movable longitudinally of the table and supporting two transverse beams, longitudinally adjustable on said carriage, each one being intended to support a set of transversely adjustable carriages.
16. In apparatus as claimed in claim 8, means adapted to lock in position the two plates of a transversely adjustable carriage, these means including springs pressing said plates on the principal carriage in order to permit an easy adjustment of said plates.
17. In apparatus as claimed in claim 11, pulleys angularly adjustable on their shafts in order to permit the adjustment of the printing-device raising means.
18. In apparatus as claimed in claim 11, a polygonal member keyed on each shaft; a finger adapted to contact with said member; and spring means pressing said finger against said member in order to maintain the shaft at a definite angular position.
19. In apparatus as claimed in claim 9, a set of perforated lugs for each printing device, said set comprising one lug having a hole of the diameter of the pin with which it is intended to cooperate, and the other lug being provided with an elongated aperture within which the cooperating pin has a liberal rectilinear play.

In testimony whereof I affix my signature.
CLAUDIUS GIVAUDAN.
